(57) **CLAIM**

The ornamental design for a shoe for swash plate type compressor, as shown and described.

DESCRIPTION

FIG. 1 is perspective view of a shoe for swash plate type compressor illustrating my new design;

FIG. 2 a front elevational view, the rear elevational view being a mirror image thereof;

FIG. 3 is a right side elevational view, the left side elevational view being a mirror image thereof;

FIG. 4 is a top plan view thereof;

FIG. 5 is a bottom plan view thereof; and,

FIG. 6 is a bottom perspective view thereof.
